UNITED STATES PATENT OFFICE.

JOHN J. SULLIVAN, OF IPSWICH, MASSACHUSETTS, ASSIGNOR, BY MESNE ASSIGNMENTS, TO THE SINGER MANUFACTURING COMPANY, A CORPORATION OF NEW JERSEY.

SEWING-MACHINE FOR FORMING GROUPS OF STITCHES.

SPECIFICATION forming part of Letters Patent No. 777,564, dated December 13, 1904.

Application filed January 12, 1904. Serial No. 188,697. (No model.)

To all whom it may concern:

Be it known that I, JOHN J. SULLIVAN, a citizen of the United States, residing at Ipswich, in the county of Essex, and State of Massachusetts, have invented certain new and useful Improvements in Sewing-Machines for Forming Groups of Stitches, of which the following is a specification, reference being had therein to the accompanying drawings.

10 In sewing buttons to garments or in mechanically performing other sewing operations with two-thread sewing-machines forming groups of stitches, as in barring or tacking or stitching buttonholes, it is desirable to 15 secure the last or severed ends of the threads, so as to positively prevent the loosening or unraveling of the stitches, and this is particularly desirable and necessary in sewing on buttons where the attaching-strokes are subjected to considerable strain and abrasions such as is liable to loosen them. It has heretofore been customary to some extent in sewing on buttons or in barring, tacking, &c., with two-thread sewing-machines to complete 20 the operation of forming each group of stitches by making two or three "fastening-strokes" which are formed in one place or needle-puncture by omitting the horizontal movements of the work or of the needle while these 25 stitches are being made; but even these interlocked or interlooped fastening-strokes are liable when the garments in which they are formed are in use to become loosened or unraveled, thus imperiling the safety or integrity 30 of the other stitches of the group.

This invention has for its object to avoid the difficulty above referred to by securely fastening together in a hard knot the ends of the two threads employed in forming groups 40 of stitches and which hard knot will positively prevent loosening or unraveling of the stitches of a group of threads serving as a button-fastening or as a bar, tack, or other purpose. This object is or may be effected 45 on a two-thread lock-stitch sewing-machine of well-known construction without adding any parts and merely by making some slight

changes in the parts heretofore employed, as will hereinafter appear.

In carrying the invention into effect the last horizontal movement given to the work or the needle in making a group of stitches will be in such direction with reference to the direction of movement of the shuttle as to cause the thread extending from the stitch last tightened into the work to the eye of the needle to be so disposed that the loop thrown out thereby to be taken by the shuttle below the work will be twisted, and when the shuttle has passed and carried its own thread through such twisted loop of needle-thread the latter will form a "half-hitch" around the shuttle-thread, so as to form a half-knot with the two threads, and if two or three half-knots be made in one place or without moving the needle or the work horizontally between two descents of the needle and be tightened together they will form a hard knot of the two threads. In other words, if a half-hitch of needle-thread be disposed about the shuttle-thread to form a "half-knot" and then another half-hitch of the needle-thread be taken around the shuttle-thread to form another half-knot the second half-knot when tightened to the first half-knot with no intervening material will form a hard knot of two threads, the ends of which next the work or material will extend from separated points in the material, so that the hard knot thus formed by the two threads at two needle descents cannot be pulled back through the needle-hole in the work or material, and the two threads may then be severed close to the work without imperiling the integrity of the completed group of stitches. The tightening together of the two half-knots to form the completed hard knot is effected mechanically by the ordinary take-up or stitch-tightening device or devices of the sewing-machine.

The invention may be carried into effect on any suitable two-thread lock-stitch sewing-machine equipped with means for shifting or feeding the work beneath the needles or for shifting the needle relative to the work in

forming groups of stitches by moving the needle or work, as a group of stitches is about to be completed, in such direction as to cause the needle to twist its own thread twice at two successive descents, as it is presented to the shuttle through the same needle hole or puncture in the work.

In the accompanying drawings, Figures 1 and 2 are opposite side views of a lock-stitch button-sewing machine by which the present invention may be carried into effect. Fig. 3 is a rear end view, and Fig. 4 a front end view, of the same. Fig. 5 is a bottom view, and Fig. 6 a partial plan view, partly in horizontal section, of the same. Fig. 7 is a detail perspective view of the double cam device for tripping the stop-motion. Fig. 8 is a detail view of the stop-motion cam. Figs. 9, 10, 11, 12, 13, and 14 are somewhat diagrammatic views illustrating the method of carrying the invention into effect, and Fig. 15 is a somewhat diagrammatic view illustrative of the completed result.

The stitch-forming mechanism of the machine (shown by the accompanying drawings) is that of a well-known form of Singer lock-stitch machine equipped with means for sewing buttons to fabrics by groups of stitches, each of which will have a predetermined number, in that the machine is provided with a stop-motion device which will be tripped automatically when a desired number of stitches have been formed, the present machine being also equipped with an automatic thread-cutting device which will sever both threads of the lock-stitch seam after said threads have been tied into a hard knot in accordance with the present invention.

The present machine, which will now be generally described, comprises the needle 12, carried by a vertically-reciprocating needle-bar 13, operated from a driving-shaft 14, journaled in the upper part of the arm 15, and an oscillating shuttle 16, located below the work-plate 17 and operatively connected in the usual manner with the said driving-shaft, which latter is in the present instance provided with a loose pulley 18 and a fast pulley 19, said fast pulley having an integral or rigidly-attached stop-motion cam 20. Pivotedly mounted at its lower end in a projection 21 on a bracket 22 is a start and stop motion lever 23, provided with a belt-shifter 24 and with a plunger 25, pressed upward by a suitable spring, the said start and stop motion lever being acted on by a coil-spring 26, having a tendency to force the upper end of said start and stop motion lever outward, but which tendency is restrained by a detent-lever 27, which serves to retain said start and stop motion lever in its inoperative position, as shown in Figs. 1 and 2. Mounted in ears 28 of the bracket 22 is a bell-crank lever 29, the lower arm of which impinges against the said start and stop motion lever, so that by depressing

the upper or outer arm of said bell-crank lever the start and stop motion lever may be forced inward to start the machine when desired. The start and stop motion lever is provided with a depending arm 30, having a slot or hole 31, the purpose of which will presently appear.

The driving-shaft 14 is provided with a worm 32, meshing with a worm-wheel 33, fixed to a shaft 34, to which is also secured a cam-wheel 35, having in its outer face cam tracks or grooves 36 and 37 and in its inner face a cam track or groove 38. The cam-track 36 is entered by a roller-stud at the upper end of a lever 39, fulcrumed in a bracket 40 and extending down through the work-plate 17. The lower end of the lever 39 is connected by a pitman 41 to a block 42, adjustable in a slot 44 of an arm 45 of a bell-crank lever fulcrumed on a stud 46 and the shorter arm 47 of which is connected by a link 48 with a sliding plate 49 beneath the work-plate of the machine. To the plate 49 is attached a plate 50, located above the work-plate of the machine. The yokes forming the ends of the pitman 41 preferably have an adjustable connection consisting of a rod 411, oppositely threaded at its opposite ends and entering threaded sleeves 412, with which said yokes are provided, so that by turning said rod by a wrench applied to its central rectangular portion 413 the working length of said pitman may be varied for convenience of adjustment when the set-nuts 414 on said rod are loosened.

The work-holder comprises upper and lower members, between which the work is yieldingly held and which are movable in any desired horizontal direction beneath the needle 12. In the present instance the upper member or presser-foot of the work-clamp is constructed as a button-holder 51, carried by an arm 52, attached to a block 53, which is in turn secured to a plate or bar 54, resting on and loosely connected to the plate 50, and which plate or bar 54 carries the movable throat-plate 55. This movable throat-plate 55 is not essential, as for many purposes the presser-foot of the work-holder might rest upon the work lying directly on a stationary throat-plate. The presser-foot of the work-holder is forced yieldingly downward by a plate-spring 56.

The lower plate or bar 54 of the work-holder is provided at its rear end with a rigidly-attached pin or post 57, received in a recess or slot of a hollow or slotted lower arm of a lever 58, fulcrumed or pivoted on the bracket 40, and the upper arm of which is provided with a pin or roller-stud entering the cam-groove 38 of the cam-wheel 35. Vertically adjustable on the pin or post 57 between the flanges of the lower hollow or slotted arm of the lever 58 is a contact-block 59, held in any desired position of adjustment by a set-screw 60. By varying the vertical position of the

adjustable contact-block 59 the extent of movement imparted to the work-holder lengthwise of the machine by the lever 58 will be varied, and by changing the position of the adjustable block 42 in the slotted arm of the bell-crank lever 45 47 the extent of movement of the work-holder crosswise of the machine will likewise be varied, as will be understood.

The present machine is preferably provided with a thread-cutting mechanism essentially the same in principle as that shown and described by United States Patent No. 702,832, granted June 17, 1902, although of a somewhat improved construction. In the present instance the thread-cutters or knives 61 62 are connected with a sector-gear 63, journaled in a bracket 64, attached to the shuttle-race cover-slide 65. Meshing with the said sector-gear is a rack 66, carried by a sliding bar 67, suitably supported beneath the work-plate of the machine and having near its rear end a block 68, constructed with a notch 69, entered by the lower end of a lever 70, pivotally mounted on a bracket 71 and provided at its upper end with a pin or roller-stud entering the cam-groove 37 in the outer face of the cam-wheel 35. The sliding bar 67 carries at its rear end a pin or roller-stud 72, engaged by the forked arm 73 of a bell-crank lever, the other arm, 74, of which is provided with a pin or block 75, having a stud 76, engaged by a spring 77, which has a tendency to press the said pin or block 75 outward toward the depending arm 30 on the start and stop motion lever 23.

35. The two levers 70 and 73 74 serve through the connections above described to impart what may be termed a "two-stage movement" to the thread-cutters from the cam-groove 37 and the stop-motion device in a manner somewhat similar to that described in United States Patent No. 702,832, above referred to, although the first-stage movement of the thread-cutters imparted thereto from the said cam-groove is in the present instance a two-step movement. Thus when a group of stitches is nearly completed the portion 371 of the cam-groove 37 will act on the pin or roller-stud at the upper end of the lever 70, and thus cause a partial forward movement to be imparted to the 50 thread cutters or knives 61 62 to cause the finger of the cutter 61 to engage the shuttle-thread, and at the next succeeding stitch the said knives or cutters will be farther advanced by the portion 372 of the said cam-groove to cause the finger of the cutter 62 to enter a loop of needle-thread. After these two steps of the first-stage movement have been effected the second or cutting stage movement of the knives or cutters, and which is a quick or sudden movement, will be imparted thereto from the stop-motion lever, as in the machine of the patent referred to, as will presently appear. The first step of the first-stage movement of the sliding bar 67, operated by the 65 lever 70, moves the bell-crank lever 73 74 far

enough to bring the spring-pressed pin or block 75 nearly into register with the hole or slot 31 in the arm 30 on the stop-motion lever 23; but before the second step of the first-stage movement of the sliding bar 67 occurs 70 the said stop-motion lever will be tripped, as will presently be described, and the arm 30 will then engage the spring-pressed pin or block 75 and force it inward on the arm 74, so that when the second step of the first-stage 75 movement of the lever 70 and of the sliding bar 67 operated therefrom is effected the lever 73 74 will be moved to bring the said block or pin 75 into register with the hole 31 of the arm 30, and into which hole said block or pin 80 will be forced by its spring, thereby coupling the cutting mechanism with the stop-motion device.

The cam-wheel 35 is provided on its inner face with a cam projection or projections 43 85 to trip the detent-lever 27 when the machine is to be stopped. When the said detent-lever is tripped, so as to be disengaged from the start and stop motion lever, the spring 26 forces the upper end of said start and stop 90 motion lever outward, and thus brings the spring-pressed plunger 25 beneath the cam 20 on the fast pulley 19. Adjacent to said cam is a notch 78, beyond which is a tappet 79. When the plunger enters the notch 78 95 and is engaged by the tappet 79, a limited movement transversely of the machine will be imparted to the start and stop motion lever against the pressure of a buffer-spring 80 in a sleeve 81 on the bracket 22 and acting on a pin or rod 83, forced against said lever by said spring. This transverse or lateral movement of the start and stop motion lever causes the arm 30 thereon to impart the final or thread-severing movement to the thread-cutters 100 through the bell-crank lever 73 74 and other connections above described.

Connected with the sector-gear 63, which operates the thread-cutters 61 62, is a movable thread-controller consisting of a thin 110 curved plate-spring 92, which presses upward against the under side of the throat-plate 93 and which serves to nip the end of the needle-thread against the throat-plate after the said thread has been severed and to hold said end 115 until it is fastened in the work by the formation of two or three stitches of the next group, as fully set forth in the application of Charles M. Horton, filed January 12, 1904, Serial No. 188,693, and in which this feature, which is 120 not of my invention, is claimed.

The needle-bar 13 is preferably provided with a thread-nipping device which is in principle similar to that of United States Patent No. 702,832, granted June 17, 1902, the present construction consisting of a tension-plate 125 84, normally springing at its lower or free end away from said needle-bar and engaged by the lower arm of a lever 85, carried by said needle-bar and arranged to be engaged 130

above its pivot or fulcrum by an arm 86 at the forward end of a sliding rod 87, having near its rear end a collar 88, engaged by the lower arm of a bell-crank lever 89, the upper 5 arm of which is yieldingly forced against the periphery of the cam-wheel 35 by a spring 90, coiled about the pivot of said lever. The stress of the said spring 90 is exerted through the lever 89, collar 88, rod 87, and arm 86 on the thread-nipping lever 85 when not restrained by the full peripheral portion of the cam-wheel 35, and the said cam-wheel has one or more notches 91 in its periphery so arranged that when the machine is about to be 15 stopped the bell-crank lever 89 will be free to be so moved by the spring 90 as to force the sliding rod 87 forward, and thus cause the thread-nipping plate 84 to grip the needle-thread.

20 The cam-wheel 35 of the present machine is of such construction as to be suitable to impart the proper movements to the work-holder for a machine for attaching flat buttons to garments either by plain or by crossing overlying stitches. For forming crossing stitches the cam-grooves 36 and 38 of the cam-wheel herein shown are made with a proper number of acting parts to make a desired number of stitches to sew on a button during each half-25 revolution of the cam-wheel, and the stop-motion-tripping cams or projections are likewise duplicated, as are also the acting parts of the cutter-operating cam-groove 37 and the thread-nipper cams or depressions. As the work-30 clamp or work-holder has diagonal movements imparted to it in making crossing stitches in sewing on flat buttons, the cams for moving the work-holder both lengthwise and crosswise of the machine are timed to act simultaneously, so 35 that the resulting horizontal movements of the work-holder will be diagonal; but if it be desired to use the machine for making a single set of button-attaching stitches, as in sewing on a flat button having only two holes or having 40 a bar across which the stitches are to be laid the movements of the work-holder lengthwise of the machine may be suspended by moving the contact-block 59 to the upper end of the lower arm of the lever 58, where it will be 45 secured in a position coincident with the fulcrum of said lever, thus rendering the movements of the latter idle, and the lever 39 will then, through the connections hereinbefore described, simply reciprocate the forward end 50 of the work-holder back and forth transversely of the machine to make a single set of button-attaching stitches or to make a plain bar of overlying stitches.

55 In sewing buttons to garments or fabrics by the machine herein shown and described the needle 12 is caused to carry its thread 94 alternately through different holes in the button 96 by shifting the button beneath the needle, the shifting movements of the button-60 holder being derived from the cam-grooves 36

and 38 in the cam 35, as has already been described. When the needle occupies a position relative to the button such as is shown in Fig. 9 and is descending for the formation of the next stitch, the section of needle-thread 70 running from the last stitch fastened in the work to the eye of the needle will extend in a direction which for want of a better term may be called "rearward" of the needle, as denoted in dotted lines in Fig. 9, so that the 75 needle-thread will be presented to the shuttle or loop-taker moving from the right toward the left, Figs. 9 and 11, in a plain loop, as denoted in Figs. 9 and 10. When, however, the needle occupies a position relative to the button 80 such as is shown in Fig. 11 and is descending to form the next stitch, the section of needle-thread running from the work to the eye of the needle will extend in front of the needle, as denoted by dotted lines in Fig. 11, so that 85 the loop of thread thrown out by the needle will be twisted, as shown in Figs. 11 and 12, and when the shuttle-thread 97 has been passed through such twisted loop of needle-thread the latter will form a "half-hitch" around the shuttle-thread, as diagrammatically illustrated in Fig. 13. This half-hitch when the stitch is tightened by the take-up 95 in the usual manner will form a half-knot and by making a second stitch or a second concatenation of the 90 needle and shuttle-threads with a twisted loop of needle-thread in the same hole in the work to make a second half-knot and then tightening the second half-knot to the first half-knot by the take-up, as before, the two threads 95 will be tied together beneath the work in a hard knot 100, as diagrammatically illustrated in Fig. 15. The arrows on the buttons (shown in Figs. 9 and 11) denote the directions of the 100 last movements of the work to bring the latter into the positions relative to the needle shown, respectively, in the two views, and it will therefore be understood that in order to bring the section of needle-thread extending from the work to the eye of the needle to the 105 position shown by dotted lines in Fig. 11, or on what may be termed the "front" side of the needle, the work or the needle must be moved in a particular horizontal direction with reference to the direction of movement 110 of the shuttle just before the formation of what may be termed the "finishing" stitches (or the stitches made by two or more descents of the needle in the same hole) are made. In order, therefore, to tie the two threads of a 115 lock-stitch seam together in a hard knot in the manner just described, it is preferable that the last horizontal or shifting movement of the work prior to the finishing stitches should be in a certain direction, and it is necessary that the needle should descend at least twice in the same place, so as to bring at least 120 two half-knots, which are formed by twisted loops of needle-thread around the shuttle-thread, together without intervening mate- 125 130

rial, so that such half-knots may be drawn up into a hard knot. To this end the cam-track 35 in the cam-wheel 35 is provided just in front of the rests 361 with certain cam projections 362, which will, through the connections hereinbefore described between said cam and the work-holder, effect the last horizontal movement of the work in a certain desired and predetermined direction, as denoted by 5 the arrow on the button in Fig. 11. This movement of the work just referred to will, as above stated, bring the section of needle-thread running from the work to the eye of the needle on what may be termed the "front" 10 side of the needle, as shown by dotted lines in Fig. 11, and thus causes the needle-loop to be twisted, as shown in Figs. 11 and 12.

To insure that the needle-thread will still be retained on the front side of the needle at 15 its next descent in the same place in the work in forming the finishing stitches, the needle 12 is preferably provided below its eye with a small spiral groove 101, which will retain the needle-thread on the front side of the needle at this second descent in the same hole in 20 the work, so as to form the second half-knot, which is to be tightened to the first half-knot in order to tie the two threads together in a hard knot, as somewhat diagrammatically 25 shown in Fig. 15. The take-up or thread-controller 95, by which the slack of the needle-thread is at all times drawn up or controlled and by which the stitches are tightened, will assist in retaining the needle-thread 30 in the spiral groove 101 near the point of the needle after the thread has been once drawn into said groove and is not displaced therefrom by subsequent horizontal movement of 35 the needle or work until the knotting operation is completed.

The locked portions of the needle and shuttle threads, when the tensions of the two threads are properly adjusted, occur in the work so that the needle-thread of the stitches shows only 40 on the upper side of the work and the shuttle-thread only on the lower side of the work; but the knot which is tied in the two threads extending toward each other from two separated places in the work will appear on the 45 lower side of the work. (See Fig. 15.) For clearness of illustration the stitches in Figs. 9, 11, and 15 are shown as being somewhat spread out, although in practice the stitches of each series are practically unspaced and 50 will overlie each other more or less, as will be understood. Also for clearness of illustration only the last-formed reinforcing-strokes of the group are shown in Figs. 10, 12, and 14, the preceding strokes of the group being 55 omitted. The cam portions 362 in front of the rests 361 in the cam-wheel 35 will effect the last shifting movement of the work in a proper direction to cause the needle-thread running from the work to the eye of the needle to be disposed in front of the needle when 60

sewing two-eyed or bar buttons to garments by a single series of stitches, as hereinbefore described, or in making a single series of barring or tacking stitches.

When the two threads of the lock-stitch 70 seam have been tied together in a hard knot, as has been described, the two threads are severed below the work by the automatic thread-cutting mechanism of the machine and the latter is automatically stopped by the stop-motion device, all as hereinbefore set forth. It will thus be understood that without adding any parts to a sewing-machine, which may be of well-known construction, and by only such slight changes of the old parts as do not materially add to the cost of the machine the present invention produces a knotting mechanism by which the two threads of a lock-stitch seam may be tied together in a hard 80 knot at the completion of a group of a desired 85 number of stitches and the two threads then be severed close to the under or back side of the work, thus not only making a neat finish, but so securely fastening the ends of the sewing-threads that they cannot get loose. 90

The invention is not to be understood as being limited to the details of construction by which it is carried into effect herein shown and described or to the particular form of group-stitch sewing-machine in which it is herein 95 illustrated as being embodied, as these may vary widely without departing from the essence of the invention. Also other means than the spiral groove near the pivot of the needle and the direction of the last movement of the 100 work prior to the finishing stitches may be employed to effect the automatic knot-tying operation.

Having thus described my invention, I claim and desire to secure by Letters Patent— 105

1. In a two-thread lock-stitch sewing-machine, the combination with stitch-forming devices, comprising a needle and a loop-taker, of work-holding and stitch-tightening devices, means for imparting relative horizontal movements to the needle and work, a stop-motion device by the assistance of which the machine is stopped when a group of a predetermined number of stitches has been formed, automatic means for causing the said needle to 115 present a twisted loop of its thread to the said loop-taker a plurality of times in succession just before the machine is automatically stopped, and automatic means whereby the relative horizontal movements of the needle and work are suspended during the time when the said twisted loops of needle-thread are presented to the said loop-taker, so that the said needle will descend through the same hole in the work a plurality of times in succession 120 to form at least two half-knots in the two threads of the lock-strokes, and which half-knots are drawn up into a hard knot by the stitch-tightening device. 125

2. In a two-thread lock-stitch sewing-ma- 130

chine, the combination with stitch-forming devices, comprising a needle and a loop-taker, of work-holding and stitch-tightening devices, means for imparting relative horizontal movements to the needle and work, a stop-motion device by the assistance of which the machine is stopped when a group of a predetermined number of stitches has been formed, automatic means for causing the said needle to 5 present a twisted loop of its thread to the said loop-taker a plurality of times in succession just before the machine is automatically stopped, automatic means whereby the relative horizontal movements of the needle and 10 work are suspended during the time when the said twisted loops of needle-thread are presented to the said loop-taker, so that the said needle will descend through the same hole in the work a plurality of times in succession to 15 form at least two half-knots in the two threads of the lock-stitches, and which half-knots are drawn up into a hard knot by the stitch-tightening device, and automatic means for severing both of the threads below the work adjacent 20 to said knot.

3. In a two-thread lock-stitch sewing-machine, the combination with a two-thread stitch-forming mechanism comprising an eye-pointed needle, having a spiral groove between its eye and point, and a loop-taker, of work-moving, work-holding and stitch-tightening devices, a stop-motion device by means of which the machine is stopped when a group of a predetermined number of stitches has 25 been formed, and automatic means, coöperating with the said spiral-grooved needle, for causing the said needle to present twisted loops of its thread to the said loop-taker through the same hole in the work a plurality of times in 30 succession just before the machine is stopped, so as to form a succession of half-knots in the two threads of the lock-stitches, and which half-knots are drawn up into a hard knot by the stitch-tightening device.

4. In a two-thread lock-stitch sewing-machine, the combination with a two-thread stitch-forming mechanism comprising an eye-pointed needle, having a spiral groove between its eye and point, and a loop-taker, of work-moving, work-holding and stitch-tightening 35 devices, a stop-motion device by means of which the machine is stopped when a group of a predetermined number of stitches has been formed, automatic means, coöperating with the said spiral-grooved needle, for causing the said needle to present twisted loops of its thread to the said loop-taker through the same hole in the work a plurality of times in 40 succession just before the machine is stopped, so as to form a succession of half-knots in the two threads of the lock-stitches, and which half-knots are drawn up into a hard knot by the stitch-tightening device.

5. In a two-thread lock-stitch sewing-machine, the combination with a two-thread stitch-forming mechanism, comprising a needle and a coöperating loop-taker, of work-holding and stitch-tightening devices, a stop-motion device by means of which the machine is stopped when a group of a predetermined number of stitches has been formed, and automatic means for imparting relative horizontal movements to the work and needle so that 50 the latter will penetrate the work at two different separated points several times alternately, to form a group of unspaced stitches, and automatic means for suspending said relative horizontal movements of the needle and work before the machine is stopped, said relative horizontal movement means being constructed to effect the last horizontal movement, prior to the stopping of the machine, in such direction, relative to the direction of 55 movement of said loop-taker, as to cause the needle to present a twisted loop of its thread to the said loop-taker through the same needle-puncture in the work a plurality of times in succession, to form a succession of half-knots which are tightened into a hard knot by the said stitch-tightening device.

6. In a two-thread lock-stitch sewing-machine, the combination with a two-thread stitch-forming mechanism, comprising a needle and a coöperating loop-taker, of work-holding and stitch-tightening devices, a stop-motion device by means of which the machine is stopped when a group of a predetermined number of stitches has been formed, automatic means for imparting relative horizontal movements to the work and needle so that the latter will penetrate the work at two different separated points several times alternately, to form a group of unspaced stitches, automatic 95 means for suspending said relative horizontal movements of the needle and work before the machine is stopped, said relative horizontal movement means being constructed to effect the last horizontal movement, prior to the stopping of the machine, in such direction, relative to the direction of movement of said loop-taker, as to cause the needle to present a twisted loop of its thread to the said loop-taker through the same needle-puncture in the work a plurality of times in 100 succession, to form a succession of half-knots which are tightened into a hard knot by the said stitch-tightening device.

7. In a two-thread lock-stitch sewing-machine, the combination with a two-thread stitch-forming mechanism, comprising a needle and a coöperating loop-taker, of work-holding and stitch-tightening devices, a stop-motion device by means of which the machine is stopped when a group of a predetermined number of stitches has been formed, automatic means for imparting relative horizontal movements to the work and needle so that the latter will penetrate the work at two different separated points several times alternately, to form a group of unspaced stitches, automatic 105 means for suspending said relative horizontal movements of the needle and work before the machine is stopped, said relative horizontal movement means being constructed to effect the last horizontal movement, prior to the stopping of the machine, in such direction, relative to the direction of movement of said loop-taker, as to cause the needle to present a twisted loop of its thread to the said loop-taker through the same needle-puncture in the work a plurality of times in 110 succession, to form a succession of half-knots which are tightened into a hard knot by the said stitch-tightening device, and automatic means for severing both of the threads below the work adjacent to said hard knot.

In testimony whereof I affix my signature in presence of two witnesses.

JOHN J. SULLIVAN.

Witnesses:

HENRY J. MILLER,
HENRY A. KORNEMANN.
